(57) **CLAIM**

The ornamental design for a mower, as shown and described.

DESCRIPTION

FIG. 1 is a right perspective view of a mower showing the new design.

FIG. 2 is a left perspective view thereof.

FIG. 3 is a front view thereof.

FIG. 4 is a rear view thereof.

FIG. 5 is a ride side view thereof.

FIG. 6 is a left side view thereof.

FIG. 7 is a top view thereof; and,

FIG. 8 is a bottom view thereof.

The broken lines shown in the drawings form no part of the claimed design.
